UNITED STATES PATENT OFFICE.

THOMAS F. BARTA, OF PISEK, NORTH DAKOTA.

HINGE.

1,321,277.

Specification of Letters Patent.

Patented Nov. 11, 1919.

Application filed June 16, 1919. Serial No. 304,458.

To all whom it may concern:

Be it known that I, THOMAS F. BARTA, a citizen of the United States of America, residing at Pisek, in the county of Walsh and 5 State of North Dakota, have invented certain new and useful Improvements in Hinges, of which the following is a specification.

The primary object of the present invention is to provide a hinge in which the leaf extensions bent to provide the knuckles of the hinge sections are adapted to be passed through openings provided in the hinge plates with the terminal edges thereof secured beneath said plates.

With the above and other objects in view, the invention consists in the combination and arrangement of parts herein fully described in connection with the accompanying drawing, and in which like reference characters indicate similar parts throughout the several views,

In the drawing,

Figure 1 is a top plan view of a hinge 25 constructed in accordance with the present invention,

Fig. 2 is a cross sectional view of the hinge and a portion of a supporting structure showing the terminal edges of the 30 knuckles of the hinge extending through the hinge plates,

Fig. 3 is a detail perspective view of a portion of one of the hinge plates with the terminal edges of the knuckles removed 35 from the slot in the hinge plate, one of the knuckles being broken away to show the plate slot,

Fig. 4 is a cross sectional view of a portion of one of the hinge plates with the 40 hinge pintle in dotted line positions showing the position of the plate knuckle before entering the plate slot,

Fig. 5 is a perspective view of a portion of one of the hinged plates showing the 45 reversed side as disclosed in Fig. 3,

Fig. 6 shows a modified form of the invention embodying the same features but showing two knuckle sections in a single hinge and

50 Fig. 7 is an edge view of the hinge shown in Fig. 1.

Describing the invention more in detail, there is provided a hinge embodying similar leaf sections 8 having the usual openings 9 therein arranged in any desired for-

mation for the reception of screws 10 or like retaining means, the plate sections 8 being secured to the support 11 shown in Fig. 2 which may be any object that is desired to hingedly connect parts thereof together.

The knuckle of the hinge includes leaf extensions 12 arranged in spaced relation as shown in Fig. 3 providing alternate clearing spaces 13 for the co-operating leaf extension 12 of the other plate section 8 so that when the plate sections are united, the adjacent leaf extensions 12 are carried by the opposite hinged plates. As illustrated in Figs. 3 and 5, the extensions 12 are 70 curved to substantially cylindrical form and carry tongues 14 at the terminal edges thereof while the base of the sections 8 are provided with slots 15 beneath the extension 12 and through which the tongue 14 is adapted 75 to be extended and retained therein by having one face engage the beveled edge 16 of said slot, this arrangement being more clearly shown in Figs. 2 and 4.

In assembling the hinged plate sections 8, 80 the pintle 17 is inserted through the co-operating knuckles 12 of the hinge as shown in Fig. 4 and the knuckles 12 are then moved into closer relationship with said pintle with the terminal ends or tongues 14 projected through the plate slots 15 and when 85 so arranged, the resiliency thereof will cause the tongues to engage the beveled walls 16 of said slot to prevent displacement of said tongues and securely hold the knuckle extensions in their proper position surrounding the pintle 17. As illustrated in Fig. 1, the pintle 17 is retained in position in the knuckle sections by the cotter pin 18.

A modified construction of the invention 90 is shown in Fig. 6, but all the essential elements are present therein, it being noted that in this form of construction, there is provided a three-plate hinge embodying a central section 19 and end sections 20 provided with the usual screw receiving openings 21 while the knuckles 12 are identical to the preferred construction, there being shown in dotted lines in this figure, the tongue extension 14 upon the knuckles 12.

While I have herein shown and described the preferred embodiments of my invention, it will nevertheless be understood that minor changes may be made in the form, combination and arrangement of parts with

out departing from the spirit and scope of the invention as claimed.

What I claim is:—

5 A butt hinge comprising a knuckle having curved alternate extensions carried by adjacent edges of the hinged plates, said plates having slots therein adjacent said curved extensions, tongues carried by the terminal ends of said extensions and an in-

clined wall forming one side of said plate 10 slot adapted to be engaged by said extension tongues when the same are passed through said plate openings with the outer wall of the slot spaced therefrom, a pintle 15 inserted through the registering knuckles and means for retaining the bolt therein.

In testimony whereof I affix my signature.

THOMAS F. BARTA.
